FIG. 1.

FIG. 2.

INVENTOR

Frederic A. Leisen.

By Charles G. Wells Atty.

UNITED STATES PATENT OFFICE

99,131

DESIGN FOR AN ELECTRIC HEATER OR SIMILAR ARTICLE

Frederic A. Leisen, Detroit, Mich., assignor to
Detroit Electric Furnace Company, Detroit,
Mich., a corporation of Michigan

Application January 11, 1936, Serial No. 60,530

Term of patent 7 years

To all whom it may concern:

Be it known that I, Frederic A. Leisen, a citizen of the United States and a resident of the city of Detroit, county of Wayne, and State of Michigan, have invented a new, original, and ornamental Design for an Electric Heater or Similar Article, of which the following is a specification, reference being had to the accompanying drawing, forming a part thereof.

On the drawing:

Figure 1 is a front perspective view of the electric heater or similar article showing my new design.

Figure 2 is a rear perspective view thereof.

I claim:

The ornamental design for an electric heater or a similar article as shown.

FREDERIC A. LEISEN.
